UNITED STATES PATENT OFFICE.

FRANK M. GARLAND, OF PROVIDENCE, RHODE ISLAND.

DESIGN FOR AN EXHIBITION-CASE.

SPECIFICATION forming part of Design No. 16,211, dated August 25, 1885.

Application filed April 23, 1885. Term of patent 14 years.

To all whom it may concern:

Be it known that I, FRANK M. GARLAND, of the city and county of Providence, and State of Rhode Island, have invented and produced a new and original Design for Exhibition-Cases, of which the following is a full, clear, and exact description, reference being had to the accompanying drawings, forming a part of this specification.

10 The essential features of my design are a central panel and panels containing pictorial representations of scenery.

In the drawings, Figure 1 is a front view of my design. Fig. 2 is an end view of the same.

15 The box or casing A is of oblong rectangular form, bearing upon its top a cover, A', of curved form, as shown. Near the base, and extending entirely around the box, is a molding, a, while at the top of the box, and extending 20 entirely around it, is a molding, a'. Below the molding a' is a third molding, a''. In the space between the moldings a' a'' are placed four oblong panels, a' a'', the panels a' at the front and back being longer than the panels a'' at 25 the ends. At each corner of the box, and rising from the molding a, is a column, B, there being four of said columns, and their capitals terminating at the base of molding a''. At each corner of the box, and between the moldings 30 a' a'', are two pilasters, b. In the capitals of

the columns B are small square panels b'. Between the moldings a' a'' and the columns B on the front and back of the box are three panels, C C' C'', the two panels C' C'' being pictorial representations of scenery. At the ends 35 of the box, and in the spaces bounded by the moldings a' a'' and columns B, are oblong panels C', which are also pictorial representations of scenery. A railing, D, extends around the top of the box and contiguous to the cover A'. 40

It is evident that various effects of coloring and material may be produced, and that various changes in matters of detail may be made without departing from the spirit of my invention.

Having thus described my invention, I claim as new and desire to secure by Letters Patent—

1. In a design for an exhibition-case, the box or body A, having the moldings a' a'' a'', columns B, pilasters b, and panels C C' C'' and 50 a' a'', as shown and described.

2. In a design for an exhibition-case, the box A, having the cover A', moldings a' a'' a'', columns B, pilasters b, rail D, and panels a' a'' b' and C C' C'', as shown and described.

FRANK M. GARLAND.
